UNITED STATES PATENT OFFICE.

GEORGE E. PALMER AND AMASA WORTHINGTON, OF CHICAGO, ILLINOIS,
AND GEORGE A. ROWELL, OF BROOKLYN, NEW YORK, ASSIGNORS TO
THE BABCOCK & WILCOX COMPANY, OF NEW YORK, N. Y.

GRATE FOR FURNACES.

SPECIFICATION forming part of Letters Patent No. 251,792, dated January 3, 1882.
Application filed August 13, 1881. (No model.)

To all whom it may concern:

Be it known that we, GEORGE E. PALMER, of Chicago, in the county of Cook and State of Illinois, AMASA WORTHINGTON, also of Chicago aforesaid, and GEORGE A. ROWELL, of Brooklyn, Kings county, in the State of New York, have invented certain new and useful Improvements relating to Grates for Furnaces; and we do hereby declare that the following is a full and exact description thereof.

We employ an inclined grate divided horizontally in sections, with provisions for moving alternate sections, as required, to promote a traverse of the fuel from the upper to the lower portion of the grate, as required. The fuel is supplied through a hopper extending across the whole upper side of the grate. It becomes heated by its contiguity to the furnace, and so soon as it touches and begins to receive air through the grate its gas ignites and burns; but the supply of air at this stage of its progress is too little for complete combustion. The gaseous product, if anthracite, coke, charcoal, or other tolerably pure carbon is employed, is not carbonic acid—the product of complete combustion—but carbonic oxide—a product of only partial combustion.

We propose to use in this furnace mainly those varieties of coal which, when heated, give off large volumes of volatile combustible matter—in other words, to use the bituminous or blazing coal. In the treatment on the upper portion of the inclined grate only partial combustion is attained; but a large proportion of the volatile material is given off and rises mingled with carbonic oxide, both gases capable of further and intense combustion under proper conditions. If these gases are allowed in this condition to strike the cooler surfaces of the boiler, they part with their heat and escape unconsumed into the atmosphere, producing visible and offensive smoke. We defend the cool surfaces of the boiler against the contact of the gases in this condition. The furnace has what we term a "deep hanging bridge," of fire-brick or analogous material capable of enduring a high temperature, which divides its upper portion into two compartments or chambers. In the first chamber the

combustible gases are liberated and mixed with air, and the whole at a high temperature brought to such condition that, on its passage under the hanging bridge and receiving additional air, complete combustion with the production of intense heat ensues. The air supplied to this volume of combustible gas in the second chamber of the furnace is itself at a high temperature. What takes place there is really the combination of a hot mixture in which there is an excess of the combustible gas with a hot mixture in which there is an excess of air.

We have demonstrated by experiment that the construction and mode of operation shown result in a complete combustion of all that is combustible in the fuel with little labor or skill. An occasional shaking of the movable portion of the grate and the supplying of a liberal quantity of coal in the hopper at the upper edge of the grate, with preferably some additional air through an additional device described farther on, result in a rapid combustion of the fuel and the utilization of the full modicum of heat which the fuel is capable of producing. A marked gain results from the invention. We present what we believe to be the correct theory; but we do not rest the claim on the correctness of the theory.

The accompanying drawings form a part of this specification and represent what we consider the best means of carrying out the invention.

Figure 1 is a central longitudinal section through the entire furnace and boiler. Fig. 2 is a central longitudinal section through the main portion of the furnace, on a larger scale. Fig. 3 is a front view of the same, partly in section.

Similar letters of reference indicate corresponding parts in all the figures.

The boiler is of the style known as "Babcock & Wilcox."

We employ an inclined grate having horizontal grate-bars assembled in two systems, each system having horizontal bars arranged in groups, which alternate with the bars of the other series—that is to say, there are five stationary bars, I, at the top of the incline, then

a considerable interval and five more stationary bars similarly marked at a lower point, then an interval and five more, and so on. These bars are bolted to or otherwise supported on 5 the fixed work at the sides, and are never moved, except in repairing or exchanging. Another system, J, is in similar divided sets, having a corresponding number of horizontal bars connected together on a sufficient framing, J', 10 with freedom to be moved considerably forward and back.

K' K' are levers or movable arms extending upward from sleeves K and engaging with J'. These levers are free to rock or oscillate on 15 sufficient fixed shafts or round bars k. The lowermost sleeve K has a socket which receives a hand-lever, L. By moving the lever L up and down, either constantly or at intervals, the entire series of levers K' K' is rocked and 20 the alternate sections of grate J are moved forward and backward between the fixed sections I.

W W' is a crank-shaft rotated slowly by a belt or gearing from the engine. (Not represented.)

X is a loop of small chain leading from the crank W' and taking hold of the hand-lever L. When this chain is thus engaged it will automatically rock the grate. The point of connection of the chain X with the lever L may 30 be shifted inward and outward, and thereby the extent of the motion varied. When it is shifted outward to its farthest extent the movement is only sufficient to take up the lost motion in the connections, and there is no actual shaking of the grate. When it is shifted inward but little the grate is shaken slightly by the moderate rotation of the crank. Under many conditions the attendant may, after a 35 few trials, find a point in which this chain may be so adjusted that the fuel will be slowly worked down on the grate automatically, as required.

M is the front side of a sufficiently capacious hopper, into which the fuel is introduced either 45 constantly or at intervals. The back face of the hopper is an inclined hollow casing, O, of cast-iron or other suitable material, through which atmospheric air is distributed into the furnace through apertures o. The air is admitted to 50 the case O, at one or both sides of the furnace, through an adjustable register, N.

P is a horizontal grate extending from the inclined grate I J to the bridge-wall or back masonry, F, which bounds the fire-space. This 55 grate P is mounted sufficiently below the fire-grate, as indicated, to allow of slicing between. A considerable part of the front side of the grate P is covered by a dead-plate, P'. Ordinary provisions (not shown) allow this grate 60 to be shaken or dropped when necessary.

The pipe G forms the lower edge of a hanging bridge, which is composed of fire-brick or other suitable refractory material, R, and extends up to the lowermost of the inclined 65 tubes B. The spaces between these lowermost tubes B from the top of this bridge R

forward are closed by fire-bricks or other suitable non-conducting material, R', forming a nearly horizontal tight platform. This platform or flooring R', which we term the "lower 70 platform," and the nearly vertical bridge R, with the stout water tube G at the base of the latter, perform the important function of separating the front portion of the fire-chamber from the rear portion thereof and from the 75 space between the tubes above. They compel the gases rising from the upper and main portion of the inclined grate I J to descend and pass close to the surface of the more advanced and thoroughly-cooked fuel on the 80 lower portion of the inclined grate I J and on the horizontal grate P. Care must be taken to rock the lever L sufficiently to move the fuel down, but not so much as to move it too fast and cause it to accumulate too thickly at the 85 bottom. A sufficient space must be left for the gases generated in the front chamber, x, to pass under the pipe G, and consequently under the entire hanging bridge G R into the rear chamber, y. At this point they meet and mingle with a current of hot gases, composed 90 largely of atmospheric air, which has passed up through the coke and cinder resting on the horizontal grate P in the base of the furnace. The combustible elements in the solid portions 95 are completely burned by receiving a large excess of fresh air on the grate P. The hot gas rising from the fuel on P has much free oxygen. The two opposite grades of gas mingle and complete the combustion of the volatile elements 100 in the chamber y in rear of the pipe G. The combustion is unusually intense. The flame is bright and short. It will now be seen that all the volatile elements of the fuel are utilized by disengaging them in the front chamber, x, and sending them downward and rearward at a 105 high temperature, mingled with not nearly air enough for the combustion, and then presenting them in the chamber y to a current of highly heated but relatively fresh air at a high 110 temperature, which has been inducted through the thoroughly utilized solid fuel at the bottom. It is easy to so conduct this operation that the combustion will be complete, nothing being left on the grate P but earthy matter, 115 and nothing going up the chimney but completely-burned gases. The hot gases resulting 120 from the complete combustion in the chamber y move upward through the zigzag spaces between the tubes B, and are by the cross-partition T and a nearly horizontal connected platform, T', compelled to traverse forward. They move upward past the front edge of what we term the "upper platform," T', then rearward, bathing the barrels A, then downward 125 between the cross-partition T and another cross-partition, U, imparting more of their heat to the tubes B, and, after moving rearward in the space under the latter, they rise and again traverse through the zigzag spaces between 130 the tubes B and are discharged into a stack. (Not represented.)

The provisions for utilizing the heat developed are closely analogous to those in the ordinary Babcock & Wilcox boiler. Our invention pertains mainly to the means for insuring a uniform and complete combustion of the fuel and generating the heat. Complete combustion is effected in a furnace requiring only moderate space and easy of manipulation.

P' is a dead-plate extending forward from the front edge of the horizontal grate. It serves to accumulate a sufficient quantity of cinder and ashes, or of fuel in a half-burned condition, and to hold such matter there in a relatively cool state. This enables us to allow a considerable space between the lower edge of the inclined grate and the top of the grate P without realizing such a heat there as to melt the iron or do any other mischief.

L' is a portable weight, provided with a hook or other convenient means of attachment, which may be removed whenever it is desired to shake the lever L, and consequently the frame J' and bars J, by hand. The chain X being removed, either by slipping its loop off the end of the hand-lever L or by disconnecting a hook or other simple attachment from the lever L or from the crank W', or from both, the lever L may be vibrated up and down as vigorously as the exigency requires. Under more favorable conditions, the chain X being connected to the crank W' at the top and to such point in the hand-lever L as shall be found to give such sufficient reciprocation to the lever, a moderate motion may be maintained constantly. The lever L may be notched on the under side to hold the chain against shifting its position, and also, if desired, on the upper side to hold the weight L' in position.

Modifications may be made in the forms and proportions within wide limits. We can adjust the angle of the fresh-air casing O by the employment of chipping-pieces at the surfaces of contact, which can be chipped off, filed, or otherwise changed, as experience with a given kind of fuel shall dictate. We can work with some success without the casing O. We can introduce a greater or less number of bars in each of the horizontal sections I and J. We can, if desired, have every alternate bar stationary and every intermediate bar movable; but we prefer the arrangement shown with alternate sets or groups of five or about that number movable and a corresponding or nearly corresponding number stationary.

Bituminous fuels vary greatly, not only in their chemical constituents, but in their mechanical conditions, in burning. Those which remain as hard lumps may be worked differently from others which become pasty when exposed to heat, and both are materially different from some grades which flake off or change to fine scales or powder before they are fully burned. Large lumps of fuel may require a removable cover on the hopper M, to prevent air from entering the furnace through the large interstices.

The throw of the crank W' may be varied

by shifting the crank-pin in a radial slot or otherwise, so as to vary the extent of motion of the chain X.

In place of the chain X, we can substitute a rigid link with a hook or other ordinary means of engaging with the lever L. We can substitute another lever to serve in this relation independent of the hand-lever L. We esteem it important that the automatic motion be capable of easy adjustment, and also of being thrown out of use entirely to allow the grate to be shaken by hand when desired.

We attach much importance to the fact that the hanging bridge R and the lower platform or furnace-roof, R', are not water-surfaces, but fire-brick or analogous material adapted to assume and maintain a high temperature, so that the gases will be first mixed with air in limited proportions and distilled into combustible gas and burned into carbonic oxide at so high temperature that all the matter will be thoroughly combined; and then that the gases thus produced will, after passing under the hanging bridge, be exposed to and mingled with the hot gases rising from the lower portion of the furnace containing an excess of air under such conditions that all the particles will be also there combined, producing carbonic acid. We incase the water-tube G in suitably-formed fire-bricks to prevent it from direct exposure to the hot gases, and thus avoid the refrigerating effect which it would otherwise produce.

The furnace having the properly-formed chambers x y thus bounded by surfaces which may be raised to a very high temperature is very different from any, however closely approaching it in form, in which the surfaces are naked portions of a boiler filled with water, and consequently maintained at a relatively low temperature. It is important that the chambers be so proportioned as to allow a proper space, with no great surplus of space, for the two operations—that is to say, the production of hot combustible gas in the first chamber, x, and the burning it completely, under the conditions prescribed, in the second chamber, y. The proportions may require to be varied with different kinds of fuel and different conditions with regard to draft. Our experiments indicate the proportions shown are about right for using soft coal from the Illinois bed burned with natural draft.

Parts of the apparatus may be used without the whole; but we prefer to employ the whole, combined and arranged about as shown. Where a number of the furnaces are employed side by side, one shaft, W, may extend across the front of the whole, with a crank, W', introduced at the front of each furnace.

We do not here claim the peculiarities of the furnace with regard to the treatment of the gases rising from the coal. Such are made the subject of a separate application for patent by one of us, George E. Palmer, and belong to him alone.

We claim as our invention—

1. An inclined grate having transverse bars lying nearly or quite flatwise, a portion being mounted stationary and another set mounted in the spaces between, being movable horizontally, as herein specified.
2. The bottom grate, P, with its front dead-plate, P', in combination with a separate inclined grate, with means for moving a portion of the latter forward and backward, as herein specified.
3. The flexible connection X, leading from a constantly-moving part, W, in combination with the hand-lever L, and with an inclined grate connected thereto, arranged to serve at will to shake the grate by power, and also to allow the grate to be shaken by hand, substantially as herein specified.
4. The combination of an inclined grate, I J, with provisions for shaking a part, a feeding-

hopper, M, for supplying fuel thereto, a horizontal grate, P, for burning the residue, and a hanging bridge, R, arranged to induce a mixture and complete combustion of the gases, as herein specified.

In testimony whereof we have hereunto set our hands this 1st day of August, 1881, in the presence of two subscribing witnesses.
